UNITED STATES PATENT OFFICE

RUSSELL J. POULIOT, OF DETROIT, MICHIGAN, ASSIGNOR, BY MESNE ASSIGNMENTS, TO DEE WITE, INCORPORATED, OF DETROIT, MICHIGAN, A CORPORATION OF MICHIGAN

OUTBOARD MOTOR BOAT

Application filed June 14, 1929. Serial No. 370,779.

This invention relates to outboard motor boats and the object of the invention is to provide a motor boat in which the outboard motor is entirely concealed within the boat 5 without destroying the lines and appearance of the boat.

Another object of the invention is to provide an outboard motor boat having a transom forward of the stern on which an outboard motor may be mounted, the boat being provided with an aperture in the bottom rearwardly of the transom through which the lower end of the outboard motor extends.

15 Another object of the invention is to provide an outboard motor boat in which the outboard motor is entirely concealed and in which the motor compartment is ventilated to withdraw the exhaust fumes therefrom.

20 A further object of the invention is to provide a transom extending across the boat forward of the stern on which the outboard motor may be mounted, the boat being provided with an aperture rearwardly of the 25 transom and a partition on each side of the aperture between the transom and the stern.

A further object of the invention is to provide an outboard motor boat of the character described having a hinged hatch extending over the rear portion of the boat 30 between the transom and the stern, protecting the outboard motor from the weather and concealing the outboard motor within the boat.

35 These objects and the several novel features of the invention are hereinafter more fully described and claimed and the preferred form of construction by which these objects are attained is shown in the accompanying drawings, in which—

40 Fig. 1 is a plan view of the stern of the boat taken below the deck.

Fig. 2 is a section taken on line 2—2 of Fig. 1.

45 Fig. 3 is an elevation of the rear end of the boat.

Fig. 4 is a section taken on line 4—4 of Fig. 1.

50 Fig. 5 is a view of the forward end of the motor hatch.

As will be noted from Fig. 3 the stern 1 of the boat is provided with an opening 2 therethrough extending above the water line. At each side of this opening 2 and within the boat, as shown in Figs. 3 and 4, is a partition 3. These partitions 3 extend forward to a transom 4 which extends across the boat and is fitted and caulked in place to prevent passage of water forward of the transom. The partitions 3 are also caulked to the transom 4 and stern 1 and to the bottom of the boat so that water cannot pass into the chambers 5 and 6 on opposite sides of the opening 2 in the rear of the boat. As will be understood from Figs. 1 and 2 the opening 2 in the rear end of the boat extends through the bottom of the boat and between the partitions 3 to the transom 4. This provides a space through which the lower end of an outboard motor may extend into the water beneath the boat.

It will be noted from Fig. 3 that the aperture 2 does not extend as high as the transom 4 but at the same time the transom 4 is low enough so that when an outboard motor is mounted thereon between the partitions 3 the outboard motor will be entirely concealed within the lines of the boat. This brings the center of gravity low in the boat so that the boat has less tendency to roll. When travelling at high speed and in making sharp turns in which the boat is banked water sometimes has a tendency to pile up against either partition 3 forming the sides of the opening for the outboard motor. In order to prevent this water from coming up over the partition 3 a plate 7 is mounted over the opening 2 and is provided with a notch 8 therein. About the notch 8 the plate 7 is provided with a downwardly extending flange 9 shown in Figs. 1, 2 and 4, and this flange 9 deflects the water downwardly and prevents it from coming up over the partition 2. It will thus be seen that even on a sudden turn where the water is thrown up quite forcibly that the flange 9 will deflect the water downwardly again and prevent its passing into the boat or splashing up onto the outboard motor. The notch 8 does not fit the outboard motor closely and therefore

the deflection of the water downwardly by the flange 9 is necessary to prevent the water from passing over the partitions 3 and transom 4 into the boat.

5 In order to enclose the motor in the rear end of the boat a hatch 10 is hingedly mounted on the coaming 11 by the hinges 12. This hatch is provided with a rounded top, as shown in Figs. 3 and 5, and is provided with 10 ports 13 in the forward end and ports 14 in the rear end as shown. This hatch may be swung upwardly to allow the outboard motor to be mounted in the rear end of the boat on the transom 4 between the partitions 3 and 15 after the motor has been properly mounted the hatch is swung down to cover the motor. A curtain 15 is attached to the forward end 16 of the hatch, as shown in Fig. 2, and extends downward forwardly of the transom 20 4 thus closing off the motor compartment from the remainder of the boat and confining the smoke and exhaust fumes of the engine to the motor compartment. In order to efficiently exhaust these fumes from the 25 motor compartment the ports 13 and 14 are provided in the forward and rear ends of the hatch respectively so that by travel of the boat in a forward direction a flow of air passes through the ports 13 and 14 in a rearward direction thus maintaining a continuous 30 flow of air through the top of the motor compartment and thus carrying the exhaust fumes out of the compartment through the ports 14 and away from the passengers in the 35 boat. The curtain 15 when not in use is rolled up within the top of the hatch as shown in dotted lines in Fig. 2.

This hatch protects the motor and in a rain storm with the curtain down forward 40 of the motor there is no danger of the motor being short circuited and by means of the plate 7 and flange 9 the water in which the boat is riding is deflected downwardly away from the motor thus preventing short circuiting of the motor by water forcing upwardly through the opening in the bottom of the boat. By carrying the opening 2 through the stern of the boat to a point above the water line, as shown in Fig. 3, 45 should the motor strike an obstruction the usual shear pin provided for this purpose will be sheared and the end of the motor may swing up into the opening 2 in the stern of the boat so that it will clear the obstruction 50 without damage to the propeller and lower end of the outboard motor.

From the foregoing description it becomes 55 evident that the device is very simple and efficient in operation, will provide an outboard motor boat in which the outboard motor is entirely concealed within the lines of the boat without destroying the effect of the boat lines and by means of the construction shown a device is provided which accomplishes the objects described.

Having thus fully described my invention, its utility and mode of operation, what I claim and desire to secure by Letters Patent of the United States is—

1. In an outboard motor boat having a stern and provided with an aperture through the bottom at the stern, the aperture also opening through the stern of the boat from the bottom and terminating at a point above the water line, a transom extending across the boat forward of the aperture and forming a water tight compartment forward of the transom the upper edge of the transom extending slightly above the top of the aperture in the stern, a pair of partitions on opposite sides of the aperture and extending between the transom and the stern and from the bottom of the boat to a point above the water line, the transom and partitions forming a water tight well and the portion of the transom between the partitions providing a mounting for an outboard motor, and a hatch hingedly mounted on the boat and covering the portion of the boat between the transom and the stern. 90

2. In an outboard motor boat having a stern and provided with an aperture through the bottom at the stern, the aperture also opening through the stern to a point above the water line, a transom extending across the boat forward of the aperture, a pair of partitions on opposite sides of the aperture between the transom and the stern, the portion of the transom between the partitions providing a mounting for an outboard motor, a hatch pivotally mounted at the stern and providing a cover for the outboard motor, the hatch being provided with ports at the forward and rear ends to allow flow of air therethrough, and a curtain attached to the forward end of the hatch and extending downwardly to the transom. 95

3. In an outboard motor boat having a stern and provided with an aperture through the bottom at the stern, the aperture also opening through the stern of the boat from the bottom and terminating at a point above the water line, a transom extending across the boat forward of the aperture and forming a water tight compartment forward of the transom, a pair of partitions on opposite sides of the aperture and extending between the transom and the stern and from the bottom of the boat to a point above the water line, a plate extending forwardly from the stern 110 to the transom at about the level of the top of the opening through the stern, said plate being notched to allow the lower end of the outboard motor to extend therethrough the portion of the transom between the partitions 115 providing a mounting for an outboard motor and the partitions being arranged to brace the transom against vibration. 120

4. In an outboard motor boat having a stern and provided with an aperture through 130

the bottom at the stern, the aperture also opening through the stern and terminating at a point above the water line, a transom extending across the boat forward of the aperture, a pair of partitions on opposite sides of the aperture between the transom and the stern, the portion of the transom between the partitions providing a mounting for an outboard motor, and a hatch pivotally mounted at the stern and providing a cover for the outboard motor, said hatch having openings in its side walls for the passage of air therethrough above the motor.

5. In an outboard motor boat having a stern and provided with an aperture through the bottom at the stern, the aperture also opening through the lower edge only of the stern, a transom extending across the boat forward of the aperture and above the water line, a pair of partitions on opposite sides of the aperture between the transom and the stern and extending from the bottom above the water line, the portion of the transom between the partitions providing a mounting for an outboard motor and a splash plate extending between the partitions, the stern, and transom and notched at the transom end to end to allow a portion of an outboard motor to extend therethrough.

30 6. In an outboard motor boat having a stern and provided with an aperture through the bottom at the stern, the aperture also opening through the lower edge only of the stern, a transom extending across the boat forward of the aperture, a pair of partitions on opposite sides of the aperture between the transom and the stern, and a hatch over the stern above the transom and partitions having openings to atmosphere.

40 7. In an outboard motor boat having a stern and provided with an aperture through the bottom at the stern, a transom extending across the boat forward of the aperture, a partition on each side of the aperture between the transom and the stern, the portion of the transom between the partitions providing a mounting for an outboard motor, and a splash plate extending between the partitions from the stern to the transom and having an opening therein to allow a portion of an outboard motor to extend therethrough.

55 8. In an outboard motor boat having a stern and provided with an aperture through the bottom at the stern, the aperture also opening through the lower end of the stern, a transom extending across the boat forward of the aperture the upper edge of which terminates slightly above the water line and slightly above the upper edge of the opening through the stern and a pair of partitions on opposite sides of the aperture between the transom and the stern.

60 9. In an outboard motor boat having a stern and provided with an aperture through the bottom at the stern, a transom extending

across the boat forward of the aperture, a partition on each side of the aperture between the transom and the stern, the portion of the transom between the partitions providing a mounting for an outboard motor, a plate mounted on the partitions and transom and extending between the transom and the stern, the said plate being notched to allow the lower end of the outboard motor to extend therethrough, and a depending flange on the said plate about the notch.

10. In an outboard motor boat having a stern and provided with an aperture through the bottom at the stern, a transom extending across the boat forward of the aperture, a partition on each side of the aperture between the transom and the stern, the portion of the transom between the partitions providing a mounting for an outboard motor, a plate mounted on the transom and partitions and extending between the transom and the stern, the said plate being provided with a notch opening toward the transom between the partitions, and a depending flange extending downwardly from the plate about the said notch.

In testimony whereof I sign this specification.

RUSSELL J. POULIOT.
